UNITED STATES PATENT OFFICE.

JOHN W. WARE, OF SAN DIEGO, CALIFORNIA.

DESIGN FOR A BADGE.

Application filed October 25, 1926. Serial No. 19,467. Term of patent 7 years.

To all whom it may concern:

Be it known that I, JOHN W. WARE, a citizen of the United States, residing at San Diego, in the county of San Diego and State of California, have invented a new, original, and ornamental Design for a Badge, of which the following is a specification, reference being had to the accompanying drawing, forming a part thereof, in which—

I claim:

The ornamental design for a badge, substantially as shown.

In testimony whereof, I have hereunto set my hand at San Diego, California, this 19th day of October, 1926.

JOHN W. WARE.
